Primary Examiner — Phillip S Hyder*Assistant Examiner* — Roselynne Cody(74) *Attorney, Agent, or Firm* — Paul N. Dunlap, Esq.; Jeffrey A. Thurnau, Esq.(57) **CLAIM**

The ornamental design for a timing belt spacer tool, as shown and described.

DESCRIPTION

FIG. 1 is a front-top perspective view.

FIG. 2 is a front elevation view.

FIG. 3 is a cross-sectional view at line 3-3 in FIG. 2.

FIG. 4 is a side elevation view.

FIG. 5 is a top plan view.

FIG. 6 is a rear elevation view.

FIG. 7 is a rear-bottom perspective view; and,

FIG. 8 is a bottom plan view.

The side cross-sectional view at line 3-3 in FIG. 2 to the right would be the mirror image of FIG. 3. The other side elevation view would be the mirror image of FIG. 4.

The broken lines in FIGS. 1, 5, 7, and 8 illustrate a feature of the timing belt spacer tool that forms no part of the claim.
